SHIPPING DEVICE

Henry Pleasants, Jr., West Chester, Pa.

Application July 6, 1934, Serial No. 733,949

1 Claim. (Cl. 229—6)

My invention relates to shipping devices or containers. The object is to provide improved means for shipping merchandise such as books, and is especially applicable to shipping books, to and from the reader, with the minimum of inconvenience as to addresses and postage.

The invention comprises a container made of light durable material, preferably of telescoping parts, such as will insure the books against injury in transit, and which shall require no supplemental wrappings. Vulcanized fibre is an example of such material.

In accordance with the present example, the outside of the container is provided with two receptacles, frames or card holders for removably inserting two cards, one card for each frame. On one side of one card, which is called the address card, is provided the name and address of the reader or customer; and on the other side is provided the name and address of the sender, merchant or library, such as a lending library. This receptacle or card holder for the address card, is preferably provided with a protecting sheet of transparent material, such as "Cellophane" or celluloid.

When sending the package to the customer, the side of the card retaining his name and address is exposed to view; when returning the book or other merchandise, the card is turned over, exposing the name and address of the original sender.

Upon each side of the other card are placed stamps to cover the postage for each direction of travel. In returning the package this stamped card is removed from its frame, reversed and reinserted in its frame to expose the postage for the return trip. By such a device all that the customer is required to do is simply to reverse the address card and the postage card in returning the book, thus avoiding trouble and possibility of error in the shipments. The stamp-containing card is not covered but is so exposed that the stamps may be readily canceled.

Referring to the drawing, which illustrates merely by way of example suitable means for the embodiment of my invention;—

Fig. 1 is a plan view.

Fig. 2 is a section on line 2, 2 of Fig. 1.

Fig. 3 is a plan of the reverse side of the address card.

Fig. 4 is a view in perspective on a reduced scale.

Similar numerals refer to similar parts throughout the several views.

55 In the example illustrated, the container com-

prises two telescoping sections 6 and 7. Upon the outer surface of section 6 are provided two frames or card holders 8 and 9. A strap 10 is provided, preferably secured to the bottom of section 7 by any suitable formation or keeper as 11, through which the strap may slide. The strap is provided with the buckle 12, whereby the elements or sections 6 and 7 may be held together with suitable pressure to prevent movement therein of the contents, such as a book.

The frames 8 and 9 are provided with any suitable securing means, such as 13 and 14, for locking the cards in the frames.

In accordance with one example, the lever 13 is pivoted as at 17 to the frame 8, as shown in Fig. 1. The lower free end of this lever 13 is adapted to snap under an offset portion 16 of the frame, thus holding the card firmly in locked position. In another example a stud 14, of type usually found in glove fasteners, is shown. By such means the cards can be secured in position or changed, without affecting, interfering with or being dependent upon the closing means of the container.

The card 15, secured in frame 8, is provided on one side with the name and address of the customer, as indicated in Fig. 1. On the other side it is provided with the name and address of the library sending the book to the customer, as indicated in Fig. 3.

A sheet of transparent material is preferably provided to cover and protect the card 15 in frame 8.

The card 16, removably secured in frame or card holder 9, is blank and is provided on each side with postage stamps in requisite amount for paying the cost of transportation by mail.

When the customer has received the container, the stamps secured to card 16 and exposed to view, will have been canceled.

When the customer has finished with the book he replaces the same in the container and reverses the cards 15 and 16, so that the name and address of the library, and the uncanceled stamps will be exposed to view. So that after delivering the same to the post office, the package will be returned to the library.

It should be noted that the address card may be used indefinitely in shipping books, or the like, to and from the customer. For this reason, it is deemed preferable to cover the card with transparent material and also to provide the more effective locking device for the frame or housing which retains this card.

The other card, the purpose of which is to carry

the necessary postage for shipment to and from the customer, must be open or exposed for purposes of cancellation, and may be discarded after the outward and return trip. It is therefore desirable that this postage-carrying card should be disassociated from and independent of the address card, the address card being of more importance, especially to prevent loss of the package. In view of the above circumstances the retaining means associated with the postage carrying card is peculiar in its simplicity and efficiency.

In the example illustrated in Figs. 1 and 2, the postage card retainer or housing 9 is made of a slightly resilient fiber sheet having flanges on both sides and at one end for clamping or riveting to the outer surface of the container. The part between the flanges is embossed or raised into a plane above that of the flanges to provide space for receiving the card, and a window opening is provided in this raised part for exposing the card as and for the purpose described. This card should be readily inserted and withdrawn from its normal position, but at the same time secured against accidental displacement. For this purpose a post 14, is provided similar to that used in the common snap glove fastener. This post has its base fastened to the middle part of the raised

front portion of the frame; so that the head end of the post will rest in close proximity to, or upon the surface of the container. When it is desired to insert or withdraw the card, it is only necessary to lift the portion of the frame which is adjacent to the post, to separate the head slightly from the surface of the container which is beneath. Upon releasing the same, the post is returned to the securing position. The above description is only meant as an example of various uses to which the invention may be applied.

What I claim is:—

In a device of the character described, a body providing a flat outer surface, a rectangular frame of sheet material having three marginal flanges in a plane parallel with but offset from the plane of the main frame, said flanges secured to said flat surface, so that the main portion of the frame is spaced from said flat surface to admit the insertion and removal to and from the frame of a card, and a post secured to and extending from the underside of the frame near the unflanged margin and midway its extension, said post having a rounded free end yieldingly held in such close proximity to the said flat surface as normally to project into the path of travel of the card.

HENRY PLEASANTS, JR.
